Nicholas Muller's Design for a **CLOCK FRONT**

3900

PATENTED MAR 15 1870

Johann Peter Beckenberg
Dave Hinckle

Nicholas Muller

Patentee

United States Patent Office.

NICHOLAS MÜLLER, OF NEW YORK, N. Y.

Design No. 3,900, dated March 15, 1870.

DESIGN FOR CLOCK-FRONTS.

The Schedule referred to in these Letters Patent and making part of the same

To all whom it may concern:

Be it known that I, NICHOLAS MÜLLER, of the city, county, and State of New York, have invented a new and ornamental Design for a Clock-Front; and I do hereby declare that the following is a full, clear, and exact description thereof, which will enable those skilled in the art to make and use the same, reference being had to the accompanying photograph forming part of this specification, in which—

The design is represented by a front view.

This invention relates to a design for a clock-front, the main features of which are two children *a a*, partly covered with drapery, sitting near the bottom edge of the design, one on each side of the pendulum-hole *b*, holding a wreath of leaves over it.

The bottom edge is formed by a broad ornamented bar, with two large arabesques in the center, which diverge toward the sides.

The dial-hole *d* is situated in the upper portion of

the design. Above it is the top edge, which consists of arabesques, grouped, as seen in the photograph, from each side of which emanates drapery, which continues to the corners of the top.

Each of the corners is surmounted by an ornamental button.

Below the drapery, on each side of the dial-hole *d*, is a medallion, one of an Indian head, the other of a female head. The whole background is embellished by suitable ornaments, as shown in the photograph.

What I claim as my invention, and desire to secure by Letters Patent, is—

The design for a clock-front, in whole and in part, as herein shown and described.

Signed this 11th day of February, 1870.

NICHOLAS MÜLLER.
